UNITED STATES PATENT OFFICE.

FRANK H. KAYLER, OF ALLIANCE, OHIO, ASSIGNOR TO AMERICAN STEEL FOUNDRIES, OF CHICAGO, ILLINOIS, A CORPORATION OF NEW JERSEY.

SIX-WHEEL TRUCK.

1,288,425.

Specification of Letters Patent. Patented Dec. 17, 1918.

Application filed November 24, 1917. Serial No. 203,677.

To all whom it may concern:

Be it known that I, FRANK H. KAYLER, a citizen of the United States, and resident of Alliance, in the county of Stark and State 5 of Ohio, have invented certain new and useful Improvements in Six-Wheel Trucks, of which the following is a specification.

This invention relates to railway car trucks, and more particularly to six-wheel 10 car trucks.

One of the objects of my invention is to equalize the load on all wheels of a six-wheel car truck without the use of complicated levers.

Another object is to improve the side bearing arrangement.

Another object is to improve the truck arrangement for the transmission and distribution of the load in a manner to meet 20 the various requirements for successful commercial operation.

Generally speaking, these and other objects are accomplished by providing, in a six-wheel truck the combination of a side 25 frame, a bridge or equalizer member operatively connected to said frame, and a bolster operatively connected to said bridge member in a manner to equalize the load on all of the wheels.

30 The invention is illustrated on the accompanying sheets of drawings, in which—

Figure 1 is a side elevation of a six-wheel truck embodying my invention;

Fig. 2 is a fragmentary plan view of the 35 same;

Fig. 3 is a sectional view taken in the planes of the irregular line 3—3 of Fig. 1;

Fig. 4 is a sectional view taken in the plane of line 4—4 of Fig. 1;

40 Fig. 5 is a sectional view taken in substantially the same plane as the one shown in Fig. 4, of a modification of my invention; and,

Fig. 6 is a sectional view taken in the plane 45 of line 6—6 of Fig. 1.

The various novel features of my invention will be apparent from the following description and drawings and will be particularly pointed out in the appended claims.

50 Referring to the figures of the drawings, it will be noted that I have provided a six-wheel truck including at each side a side frame including a plurality of members 10

and 11 pivotally connected, adjacent the middle wheels, at their inner ends by a pin 51 12, whereby the side frame members 10 and 11 may oscillate in a vertical plane in accordance with track irregularities encountered when the grade of the road varies. These side frame members 10 and 11 have 60 bolster openings 13 and 14, respectively, and spring openings 15 and 16, respectively. Mounted over the springs 8 and 9, which are located in the spring openings 15 and 16, are caps 17 and 18 respectively, having 65 squared heads which fit into grooved recesses 19 and 20, respectively, formed in opposite ends of an equalizer 21 which bridges the springs 8 and 9. The top portion 22 of the equalizer 21 forms a side bearing for the 70 car, thus transferring the side bearing load directly to the springs 8 and 9 without transferring this load through the bolster. In the upper side of the equalizer 21 near the ends thereof there are provided pockets 23 75 and 24, respectively, for the reception of bolster arms or members 25 and 26, respectively, which are formed integrally with a central bolster 27.

It will be noted that the bolster openings 80 13 and 14 are located centrally between the end and middle pairs of wheels and that the spring openings 15 and 16 are located at distances one-third from the end pairs of wheels and two-thirds from the central pair 85 of wheels. In this manner the load is equalized on all wheels. The load from the central bolster 27 is transferred to the springs 8 and 9 through the equalizer 21, the bifurcated ends of which rest on the spring 90 plates or caps 17 and 18.

With this arrangement the bolsters or bolster members 25 and 26 may be combined into an integral structure with the central bolster 27. Due to the fact that the bolster 95 arms 25 and 26 are located centrally between the wheels, the size of the ends passing through the side frame is not limited. It is also obvious that with the arrangement as shown, it is unnecessary to use separate column guide pieces bolted on the end of the bolster, which is necessary in some designs of six-wheel trucks. The side frames are maintained in vertical position in the same manner as all flexible side frames of this 100 general type including the application of

the load thereto at points below the journal boxes producing in effect a pendulum arrangement.

Referring particularly to Fig. 5, I have shown therein a modification to be used in connection with a three-piece flexible bolster if used in the place of the unit bolster shown in the other figures of the drawings. In the construction shown in Fig. 5, the flexibility is increased between the equalizer and the end of the bolsters 27 by means of the casting 28, the ends of the bolsters and casting 28 having coöperating curved bearing portions 29. In both of these constructions, the load is thus distributed equally upon the ends of the equalizer 21, while the side motion and excessive flexibility are limited by recesses 30 in the bolsters which interlock with the bridge member, as shown best in connection with Fig. 2 of the drawings.

By means of the arrangement of the parts in this six-wheel truck, the load is evenly distributed in a simple manner, avoiding a complicated system of levers which heretofore has been used. At the same time the transmission and the distribution of the load are improved, the parts being so connected and coöperating in a manner to meet all of the requirements for successful commercial operation.

It is obvious that there may be various modifications of the invention herein particularly shown and described, and it is my intention to cover all such modifications which do not involve a departure from the spirit and scope of the invention as set forth in the following claims.

I claim:

1. In a six-wheel truck, the combination of a side frame, springs carried thereby, an equalizer operatively connecting said springs, and a bolster carried by said equalizer.

2. In a six-wheel truck, the combination of a side frame, springs carried thereby intermediate the wheels of said truck, an equalizer operatively connected to said springs, and a bolster through which the load is transmitted to said equalizer.

3. In a six-wheel truck, the combination of a side frame, springs carried thereby, an equalizer operatively connecting said springs, and a central bolster having portions at each side operatively connected to different portions of said equalizer for transmitting a load thereto.

4. In a six-wheel truck, the combination of a side frame, springs carried thereby, an equalizer connecting said springs, and means for transferring the load to said equalizer whereby the load will be equally distributed to all of the wheels.

5. In a six-wheel truck, the combination of a side frame, an equalizer operatively

connected to said side frame at points intermediate the truck wheels, and bolster members supported by said equalizer at points intermediate said wheels whereby the distribution of the load on all of said wheels is equalized.

6. In a six-wheel truck, the combination of a side frame, springs carried thereby and being located twice as far from the middle wheels as they are from the end wheels, an equalizer bridging said springs, and bolster members resting on said equalizer whereby the load transmitted to said equalizer will be equally distributed on all of said wheels.

7. In a six-wheel truck, a side frame, a bolster carrying equalizer operatively connected to points on said side frame which are more remote from the middle wheels than they are from the end wheels, whereby the load transmitted through said equalizer will be equalized on all of said wheels.

8. In a six-wheel truck, the combination of a side frame, an equalizer operatively connected to points on said side frame which are more remote from the middle wheels than they are from the end wheels, and bolster members operatively connected to said equalizer at points intermediate said wheels for equalizing the distribution of the load on said wheels.

9. In a six-wheel truck, the combination of a side frame, an equalizer operatively connected to points on said side frame which are twice as far from the middle wheels as they are from the end wheels, and bolster members operatively connected to said equalizer at points half way between said middle and end wheels whereby the load is equally distributed upon all of said wheels.

10. In a six-wheel truck, the combination of a side frame, springs carried thereby twice as far from the middle wheels as they are from the end wheels, a member bridging said springs, and bolster members operatively connected to said bridging member at points half way between said middle and end wheels.

11. In a six-wheel truck, the combination of a side frame, and a bolster carrying member bridging points on said side frame intermediate the middle and end wheels, a portion of said bridging member forming a side bearing.

12. In a six-wheel truck, the combination of a side frame, a member bridging points on said side frame intermediate the middle and end wheels, a portion of said bridging member forming a side bearing, and bolster members carried by and being operatively connected to said bridging member at points intermediate said middle and end wheels.

13. In a six-wheel truck, the combination of a side frame including a plurality of pivotally connected members, an equalizer operatively connected to points of said mem-

- bers intermediate the middle and end wheels, and bolster members engaging said equalizer for transmitting part of the load to said side frame members through said equalizer.
- 5 14. In a six-wheel truck, the combination of a side frame including a plurality of pivotally connected members, springs carried by said members at points intermediate the middle and end wheels, a member bridging
- 10 said springs and having a portion forming a side bearing whereby part of the load may be transmitted to said springs independently of bolsters, and bolster members operatively connected to said bridging member
- 15 for transmitting a portion of the load to said springs through said bridge member.
- 15 15. In a six-wheel truck, the combination of a side frame, an equalizer operatively connected to points on said side frame intermediate the middle and end wheels, and
- 20
- bolster members having interlocking portions with said equalizer to prevent excessive side motion.
16. In a six-wheel truck, the combination of a side frame, an equalizer having bifurcated portions operatively connected to points on said side frame intermediate the middle and end wheels and arranged on opposite sides of said side frame, and bolster members operatively connected to said equalizer intermediate the middle and end wheels for equalizing the load on all of said wheels.
- 25
- 26
- Signed at Alliance, Ohio, this 20th day of November, A. D. 1917.
